DOSEER

Robert Lee Humbard, Lake Arrowhead, Calif.

Application June 27, 1935, Serial No. 28,725

5 Claims. (Cl. 221—147)

This invention relates to a doser, that is, a glass or receptacle of the type generally used in mixing beverages.

An object of the present invention is to provide a doser which may be readily applied to the mouth of the receptacle containing the beverage so as to facilitate the measuring of the beverage.

The invention together with its objects and advantages will be best understood from a study of the following description taken in connection with the accompanying drawings wherein:

Figure 1 is an elevational view of the doser shown applied to a bottle.

Figure 2 is an elevational view of the doser taken at right angles to Figure 1 and with parts broken away.

Figure 3 is a vertical sectional view through the doser applied to the bottle.

Figure 4 is a horizontal view taken substantially on line 4—4 of Figure 3.

Figure 5 is a perspective view of a slide.

Figure 6 is a perspective view of a valve assembly.

Referring to the drawings by reference numerals it will be seen that the improved doser provides a transparent receptacle 5 of glass or other suitable transparent material and preferably of the shape shown. The receptacle 5 is confined within a jacket, of metal or other material. This jacket includes a flat wall portion 6 that fits substantially against one side wall portion of the receptacle 5 and top and bottom straps 7 and 8, and an intermediate strap 9 that embrace the receptacle 5 as shown.

In its top, the receptacle 5 is provided with a pouring opening 10 and in its bottom is provided with an enlarged opening having an inwardly directed flange 11. Fitted in the bottom of the receptacle 5 is a cork 12 provided with a groove 13 in which fits the flange 11 as clearly shown in Figure 3. The cork 12 is adapted to fit in the neck 14 of a conventional bottle as clearly shown.

Suitably anchored within the receptacle 5 and secured to the flat wall of the receptacle in any suitable manner is a guide 15 having openings in the top and bottom thereof through which works a valve stem 16 provided on its respective opposite ends with valve plugs or corks 17 and 18 respectively. The valve plug or cork 17 is adapted to close the opening 10 while the cork 18 is adapted to close the opening 12a through the cork 12. The stem 16 is provided intermediate its ends with a knob 19 that works through

aligned slots 20 and 21 provided respectively in the flat side of the receptacle 5 and the flat side 6 of the jacket.

For the aligned slots 20, 21 there is provided a slide closure 22 that works in a space between the side 6 of the jacket and the flat side of the receptacle 5. Intermediate its ends the slide closure 22 is provided with an opening 23 through which the operating stem 19 extends as shown in Figures 3 and 4.

Cork 17 is normally seated within the pouring opening 10 of the receptacle through the medium of a spring 24 anchored at one end to the side 6 of the jacket as at 25 and secured at its opposite end to the stem 19 as shown.

In actual practice, when it is desired to pour the measured amount of liquid from the bottle 14 into the glass, the doser is applied to the neck of the bottle 14 in the manner thought apparent. Bottle 14 is then inverted and liquid will flow from the bottle 14 into the receptacle 5. The receptacle 5 being transparent, one may readily ascertain the amount of liquid in the glass 5. When the desired amount of liquid is within the glass 5 the operator with his thumb pressed against the knob 19 and against the action of spring 24 moves the valve member 18 to close the opening through the cork 12 thus unseating the valve member 17 and permitting the contents of the doser to pass into the glass or other receptacle provided.

From the above it will be apparent that a doser of this nature will prove a great aid to bartenders and the like in mixing drinks and will otherwise meet the requirements of a doser and a liquid measuring device.

Having thus described the invention, what is claimed as new is:

1. A doser of the character described comprising a transparent receptacle having at least one flat side, a jacket for the receptacle having a flat side disposed adjacent to the flat side of the receptacle, and straps encircling the receptacle adjacent the upper and lower ends thereof and intermediate said ends respectively, said receptacle being open at each end thereof, a cork fitted in one end of the receptacle and having a passage therethrough, a valve guide fixedly mounted within the receptacle, a valve stem operating through said guide, a valve cork on one end of the stem for controlling the open upper end of the receptacle, a valve cork on a relatively opposite end of the stem for controlling the passage through the first named cork, and means

operable externally of the receptacle for shifting said stem.

2. A doser of the character described comprising a transparent receptacle having at least one flat side, a jacket for the receptacle having a flat side disposed adjacent to the flat side of the receptacle, and straps encircling the receptacle adjacent the upper and lower ends thereof and intermediate said ends respectively, said receptacle being open at each end thereof, a cork fitted in one end of the receptacle and having a passage therethrough, a valve guide fixedly mounted within the receptacle, a valve stem operating through said guide, a valve cork on one end of the stem for controlling the open upper end of the receptacle, a valve cork on a relatively opposite end of the stem for controlling the passage to the first named cork, said receptacle and jacket having aligned slots in the flat walls thereof, a manipulating knob for said stem operating through the aligned slots, and a spring device mounted on the jacket and engaged with the knob for normally urging the valve stem in one direction.

25. 3. A doser of the character described comprising a transparent receptacle having at least one flat side, a jacket for the receptacle having a flat side disposed adjacent to the flat side of the receptacle, and straps encircling the receptacle adjacent the upper and lower ends thereof and intermediate said ends respectively, said receptacle being open at each end thereof, a cork fitted in one end of the receptacle and having a passage therethrough, a valve guide fixedly mounted within the receptacle, a valve stem operating through said guide, a valve cork on one end of the stem for controlling the open upper end of the receptacle, a valve cork on a relatively opposite end of the stem for controlling the passage to the first named cork, said receptacle and jacket having aligned slots in the flat walls thereof, a ma-

nipulating knob for said stem operating through the aligned slots, a spring device mounted on the jacket and engaged with the knob for normally urging the valve stem in one direction, and a slide closure for said slots operating between the flat sides of said receptacle and jacket and having an aperture therethrough and through which said knob extends. 5

4. A doser of the class described comprising a receptacle open at each end, an axially bored cork projecting outwardly from one end of the receptacle and adapted to be inserted in the neck of a bottle or the like, a jacket embracing said receptacle, said receptacle and jacket having adjacent walls thereof provided with aligned slots, 10 a slide plate confined between said adjacent walls of the jacket and receptacle for substantially closing said slots, a valve operating member mounted on said slide plate and having respective opposite ends working in said slots, a valve stem on the 15 inner end of said valve operating member, and valve elements on the respective opposite ends of said stem for controlling respectively the bore of said cork and the open upper end of said receptacle. 20

25. 5. A doser of the character described comprising a receptacle open at each end thereof, a cork having an end fitted within one end of the receptacle, said cork being provided with an axial bore, and said receptacle having a slot in one side 30 thereof and also having an elongated recess in said one side, a slide plate for said slot operating in said recess, a valve manipulating handle mounted on said slide plate and having an end extending into said receptacle, a valve stem on 35 said end of said handle, and extending longitudinally of said receptacle, and valve members on the respective opposite ends of said stem for controlling respectively the bore of said cork and the open end of said receptacle. 40
